Hampshire

UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE

SEPARABLE FASTENER.

1,300,573.

Specification of Letters Patent. Patented Apr. 15, 1919.

Application filed July 1, 1918. Serial No. 242,696.

To all whom it may concern:

Be it known that I, FRED S. CARR, a citizen of the United States, and a resident of Newton, in the county of Middlesex, Commonwealth of Massachusetts, (whose post-office address is care of Carr Fastener Company, Cambridge, Massachusetts,) have invented an Improvement in Separable Fasteners, (A,) of which the following description, in connection with the accompanying drawings, is a specification, like characters on the drawings representing like parts.

This invention pertains to separable fasteners, and particularly, though not exclusively, to stud and socket fasteners separable by relative tipping movement in one direction only.

In the drawings, which show a preferred form of my invention:

20 Figure 1 is a front elevation of one embodiment of my invention;

Fig. 2 is a section, partly in elevation, on the line 2—2 of Fig. 1;

Fig. 3 is a rear elevation, partly in section, on the line 3—3 of Fig. 2; and

Fig. 4 is a section, partly in elevation, on the line 4—4 of Fig. 2.

In the preferred illustrative embodiment of my invention shown in the drawings, I have provided a stud 5 having a head 6 and a neck 7, a preferably abrupt shoulder 8 being provided between the head 6 and neck 7. The stud 5 is shown secured to a curtain 9 by prongs 10 passing through the curtain 30 and clenched over a plate 11 in the usual manner. Coöoperating with the stud 5 I provide a socket preferably, as shown, carried on the inner side of a curtain and secured thereto by a tubular projection 12 from the socket 35 and proper expanded or rolled over a face plate 13. The socket proper preferably comprises a front plate 14 from which the tubular extension 12 may be died forwardly, a back plate 15, which, as shown, preferably operates with the front plate 14 to provide a 40 casing for yielding jaw means herein typified by the jaw 16 below the stud and urged toward the stud by a spring 17. The casing also preferably provides a fixed jaw 18 45 adapted to engage the neck of the stud opposite the yielding jaw 16. The yielding jaw 16 is preferably beveled or inclined at that portion thereof engaging the stud, so that when the bottom portions of the stud

and socket are moved apart as by a pull to the left on the curtain 12 below the socket, the shoulder on the stud will engage the sloping surface on the yielding jaw 16, causing it to be forced downwardly against the pressure of the spring 17, thereby permitting the stud, on continuation of the relative tipping movement, to be disengaged from the fixed jaw 18, and to be entirely withdrawn from the socket.

The fixed jaw is preferably, as shown, formed by pressing forwardly a portion of the back plate 15, and the tubular projection from the plate 14 is preferably formed to provide an extended bearing surface for the head of the stud. The back plate 15 may be provided with a lip 19 providing an extended bearing surface for the shank of the stud.

While I have shown and described a preferred form of one embodiment of my invention, it will be understood that major changes involving omission, substitution, alteration and reversal of parts, and even changes in the mode of operation, may be made without departing from the scope of my invention, which is best defined in the following claims.

Claims:

1. A separable fastener comprising, in combination, a stud having a head and a neck, a socket for engagement with said stud and providing a yielding jaw having a sloping surface for engagement with the shoulder on said stud behind the head thereof, said jaw and said shoulder being relatively proportioned so that the sloping portion only of the jaw engages said shoulder.

2. A separable fastener comprising, in combination, a stud having a head and a neck, a socket for engagement with said stud and providing a yielding jaw having a sloping surface for engagement with the lower shoulder on said stud behind the head thereof, said jaw and said shoulder being relatively proportioned so that the sloping portion only of the jaw engages said shoulder.

3. A separable fastener comprising, in combination, a stud having a head and a neck providing an abrupt shoulder between them, a socket for engagement with said stud and providing a yielding jaw having a sloping surface for engagement with the shoulder on said stud behind the head there-

of, said jaw and said shoulder being relatively proportioned so that the sloping portion only of the jaw engages said shoulder.

4. A separable fastener comprising, in combination, a stud having a head and a neck, a socket for engagement with said stud and providing a fixed jaw above said stud and a yielding jaw below said stud, said stud having an abrupt shoulder between said head and neck, and said yielding jaw hav-

ing a sloping portion engaging said shoulder.

5. A socket for a separable fastener comprising a front plate, a back plate, a stud, engaging rigid jaw projecting forwardly 15 from said back plate and a yielding jaw between said plates.

In testimony whereof, I have signed my name to this specification.

FRED S. CARR.
